COVERED SLIDE FASTENER

David Silberman, New York, N. Y., and Edward J. Conlin, New Britain, Conn., assignors to Ideal Fastener Corporation, New York, N. Y., a corporation of New York

Application April 21, 1936, Serial No. 75,512

3 Claims. (Cl. 24—205)

This invention relates to separable fasteners, being specifically directed to covered separable slide fasteners.

Up to the present time, in the use of separable slide fasteners, considerable sales resistance has been encountered due to the fact that the exposed fastener elements, being metallic, disclose a zigzag metallic surface which not only is unsightly, but provides for a rough, cold and undesirable surface contacting with body portions.

Considerable efforts in the past have been devoted to remedying such condition and, along such line, covers have been applied to the length of metallic fastener elements, as, for example, stitching a separate cover strip for the fastener elements to the stringer or tape carrying the same, all of which is expensive and cumbersome, causing a thickness of the tape formation and of the closure formed by the separable fastener. Other efforts to remedy this deficiency have been directed to the bending over of a tape upon itself and over the top of the fastener surfaces, with the result that special means are required to maintain the tape and the portion thereof forming the cover over the upper surface of the fasteners, and, what is a more serious difficulty, the slider which opens or closes the separable fastener jointure is not adapted to cooperate with such form of cover, thus making necessary the design of a special means of fastening for the cover.

Broadly, it is an object of this invention to provide a covered separable slide fastener, wherein in the tape or stringer upon which the separable elements of the slide fastener are carried forms both the cover for the slider fastener elements and the medium for attaching the unit to the article to which it is applied.

It is an object of this invention to provide for a covered separable fastener, wherein the tape carrying the fastening elements is mounted in a slot extending transversely and downwardly of the fastener elements, at a point intermediate of its edges, and one portion of the tape extends away from the fastener for fastening to the article to which the device is applied, while the other portion of the tape extends over the meshing portions of the fastener elements, the normally exposed tops of the fastener elements through such medium being covered by one tape or single thickness of material at one level with the fastener elements themselves being disposed out of sight.

Specifically, it is an object of this invention to

provide a covered separable slide fastener, wherein a tape or stringer having a bead intermediate of its edges and nearer one edge than the other, is mounted with respect to a series of fastener elements so that the bead of the tape or stringer is disposed and locked within a slot extending transversely of the fastener elements from the top of each fastener element part way across the depth thereof, whereby the portion of the tape forming the cover for the fastener elements and the portion of the tape forming the fastening means to which the separable fastener closure is attached, is a single thickness of material.

Still further, it is an object of this invention to provide for covered separable slide fastener devices, wherein the tape or stringer associated with the fastener elements is beaded intermediate of its edges, and the bead portion of the tape disposed in a slot extending transversely of the top of the fastener elements, so that the surface of the tape or stringer consists of a single strip of material substantially in one plane, there being applied to this tape and fastener assembly a slider having a flanged surface acting on the substantially uncovered bottom portion of the fastener elements and a flat surface parallelly disposed with respect to the plane of the tape and contacting with that portion of the tape between the bead and the interlocking edges of the fastener, so that as the slider is actuated to seal the closure to which the separable fastener is applied, the meshing portions of the fastener are interlocked and the edge of the tape covering the fastener acted upon by the flat surface of a slider to maintain the normally flat tape edge in position, so that a complete cover is provided for the separable fastener jointure.

These and other advantages, capabilities and features of the invention will appear from the subjoined detailed description of one specific embodiment thereof illustrated in the accompanying drawing, in which

Figure 1 is a plan view of the covered separable fastener.

Figure 2 is a front elevation in section taken along lines 2—2 of Figure 1.

Figure 3 is a perspective view partly in section of one element of the covered separable fastener.

Figure 4 is a front elevation of one of the fastener units.

Figure 5 is a perspective view of a covered separable fastener embodying a different embodiment of the tape.

Referring to the drawing, numerals 11 and 12 represent fastener elements which are connected respectively to tapes 13 and 14, the fastener elements being arranged in alternation, and have the conventional projection and recess formation to provide for interlock and separation when the slide fastener is closed or opened through the reciprocation of slider 15.

Referring to Figures 2 to 4 inclusive, each fastener element comprises a head portion 16 and cooperating jaw portions 17 and 18, which jaws define a slot 19 extending transversely of the element from the top surface 20 part way across the width or depth thereof.

15 The fastener elements 11 and 12 are symmetrical and each head portion 16 includes a projection 21 on one end thereof and a mating recess 22 on the other end, the respective projections and recesses being so disposed as to provide, upon 20 engagement, for example, of projection 21 of a fastener element in series 12, with groove 22 in series 11, to hold such engaged fastener elements in horizontal alignment as shown in Figure 2.

As indicated in Figures 2 to 5 of the drawing, 25 the fastener elements are substantially curved in contour, all edges of the head and jaws being rounded and the portion thereof defining the jaw 18 when the same is attached to the tape being essentially semi-circular in conformation.

30 As shown specifically in Figure 3, one form of tape 14, involving an offset bead formation, comprises a main attachment portion 23, a bead portion 24, and the fastener head cover portion 25, the particular tape in this embodiment being a 35 woven element in which, intermediate of the edges thereof, there is interlocked the cord or bead 24, the bead substantially replacing some of the warp threads of the woven tape, while adjacent weft threads surround opposite semi-circular surfaces or sections of the tape, the alternate weft threads being in the same plane. In this form of tape the bead is so positioned as to form a substantial offset projection with respect to the normal plane of the tape, and particularly one face 40 of the tape.

45 As shown in Figure 3, the normally flat tape 14 intermediate the ends of which is interlocked the bead 24, is disposed in the fastener element shown in Figure 4, so that the bead 24 is completely disposed in substantially circular slot 19, after which the jaw 18 is pressed in a right angular direction to the dotted line position of Figure 4 as designated by the arrow, to form the closure for the tape in conjunction with jaw 17, the edge portions 26 and 27 of the jaws 17 and 18 serving to press against sections of attachment and fastener cover portions 23 and 25 adjacent the bead to form a secure clamp for the bead and tape.

50 The tape, before clamping of the fastener elements thereto, is normally in a horizontal plane, except for the bulge of the bead interlocked therewith; and after the clamping of the bead by the jaws 17 and 18 in the slot 19, the main attachment portion 23 and fastener head cover portion 25 of the tape substantially retain their normal flat position on the top surface 20 of the fastener, the fastener head cover portion 25 being of such length as to extend almost but not quite to the edge of the head 16 of the fastener, so that 55 when two fasteners of the series 11 and 12 interlock the edges of the fastener head cover portions 25 of the respective tapes abut one another and the fastener head cover portions form a closure covering the fastener elements centrally of the 60 fastening element, completely concealing the

metallic fastener elements as shown at the bottom of Figure 1.

In order to operate the slide fastener, the slider 15 associated therewith is constructed to provide flanged bottom element 30, and flat top element 31 connected by the usual cam or separator applied in such devices (here not shown), the bottom element 30 having upstanding flanges 32 of spreading wing formation, gradually decreasing in width from edge 33 to 34, the last named edge to 10 be disposed adjacent the peripheral surface of jaws 18 of the fastener, to provide proper interlocking of the fastener elements. The upper plate 31 of the slider is flat and of the same width and spread wing formation as the bottom element, 15 and is adapted to press against the tape surfaces 23 and 25, as the slider is reciprocated by actuation of the handle 35 attached to the top plate. Since any conventional cam of the type well known in the art may be disposed in the slider 20 between the plates 30 and 31 to act on the fastener elements to separate the same, no showing has been made in the present drawing.

It is to be understood that a slight clearance should prevail between flat plate 31 and the upper 25 surface of the sections 23 and 25 of tape 14, so that such plate in the movement of the slider will serve merely to smooth rather than frictionally press or rub the sections 23 and 25, particularly section 25, since both of these sections normally rest 30 against the top surface of the fastener element.

In the modification shown in Figure 5, the tape 14, instead of being woven to provide an offset 35 bead which is centrally disposed with respect to the tape and has substantially equal projections or bulges with respect to each face of the tape. As shown, the tape comprises main attachment and fastener cover portions 23 and 25 and bead 36 40 interlocked between weft threads in a manner as to project equidistantly on opposite sides of the normal horizontal plane of the tape. The flat tape carrying the bead of such configuration is inserted in the slot 19 of the fastener element and 45 jaw 18 pressed inwardly in the direction shown in Figure 4, with the result that the cord or bead is surrounded as at 37 and 38 by adjacent portions of the tape sections 23 and 25, which are pressed thereagainst, and the edges 26 and 27 50 of the jaws 17 and 18 press against the tape sections, to provide a firmly clamped neck formation, whereby the tape is locked to the fastener, and establishing the flat surface in one plane of sections 23 and 25 of the tape, for the purposes 55 specified.

Associated with the fastener elements and the slider is concealed stop 45, which is clamped to the bead formation of the respective tapes to form a terminal for the closure slit.

As is clearly shown in the drawing, the tape, including the sections thereof, applied for attachment to material for making the closure and the section for covering the head of the fastener element, are of a single thickness of the same material and are in the same plane.

Further, the closure formed by the covered slide fastener formation provides a flat top surface with no projections and with the main body of the fastener elements and the slider concealed 70 below the level or plane of the tape, which tape forms the exposed or viewable section of the closure.

It is obvious that various changes and modifications may be made to the details of construc- 75

tion without departing from the general spirit of the invention as set forth in the appended claims.

We claim:

- 5 1. In a slide fastener assembly, opposing series of fastener members, each of which has head and jaw portions, the head incorporating mating elements, the jaw portions defining a slot extending transversely from one side edge part way across the depth of the fastener member, a tape for each series of fastener members having a bead spaced from the edges and projecting beyond both faces thereof, said bead and the portions of the tape adjoining the bead being insertable in the slot of the fastener member and the jaw portions of the latter serving to clamp the bead adjoining portions of the tape to secure the tape to the fastener member, one edge of each tape serving to overlie the head and the other edge of the tape serving to overlie the jaw portions of the fastener member, the edges of said tape lying in a horizontal plane and a slider cooperating with the opposing series of fastener members for interlocking and separating the same, the respective fastener members upon interlocking being covered by said tapes.
- 10 2. In a slide fastener assembly, opposing series of fastener members, each of which has head and jaw portions, the head incorporating mating elements, the jaw portions defining a slot extending transversely from one side edge part way across the depth of the fastener member, a tape for each series of fastener members having a bead intermediate of its edges and projecting beyond both faces thereof, said tape being mounted on the fastener so that the bead rests in the slot and portions of the tape adjoining the bead are bent towards each other to overlie the bead and to form an upstanding neck, said neck being clamped by the free ends of the jaw portions of the fastener member to secure the tape to the fastener member, one edge of each tape serving to overlie the head, and the other edge, the jaw portions of the fastener member, the edges of said tape lying in a plane parallel to the upper surfaces of the head and jaw portions of the fastener member, and a slider cooperating with the opposing series of fastener members for interlocking and separating the same, the respective fastener members upon interlocking being covered by said tapes.
- 15 3. In a slide fastener assembly, opposing series of fastener members, each of which has head and jaw portions, the head incorporating mating elements, the jaw portions defining a slot extending transversely from one side edge part way across the depth of the fastener member, a tape for each series of fastener members having a bead spaced from the edges and projecting beyond both faces thereof, said bead and the portions of the tape adjoining the bead being insertable in the slot of the fastener member and the jaw portions of the fastener member having a bead spaced from the edges and projecting beyond both faces thereof, said bead and the portions of the tape adjoining the bead being insertable in the slot of the fastener member, the said bead adjoining portions being bent over towards one another to overlie the bead, and the jaw portions of the fastener serving to clamp the bent over bead adjoining tape por-

tions to secure the tape to the fastener member, one edge of each tape serving to overlie the head and the other edge of the tape serving to overlie the jaw portions of the fastener members, the tape being of a single thickness of material and the edges thereof lying in substantially a horizontal plane, and a slider cooperating with the opposing series of fastener members for interlocking and separating the same, the respective fastener members upon interlocking being covered by tapes in the same plane.

10 15 20 25 30 35

3. In a slide fastener assembly, opposing series of fastener members, each of which has head and jaw portions, the head incorporating mating elements, the jaw portions defining a slot extending transversely from one side edge part way across the depth of the fastener member, a tape for each series of fastener members having a bead intermediate of its edges and projecting beyond both faces thereof, said tape being mounted on the fastener so that the bead rests in the slot and portions of the tape adjoining the bead are bent towards each other to overlie the bead and to form an upstanding neck, said neck being clamped by the free ends of the jaw portions of the fastener member to secure the tape to the fastener member, one edge of each tape serving to overlie the head, and the other edge, the jaw portions of the fastener member, the edges of said tape lying in a plane parallel to the upper surfaces of the head and jaw portions of the fastener member, and a slider cooperating with the opposing series of fastener members for interlocking and separating the same, the respective fastener members upon interlocking being covered by said tapes.
